(57) **CLAIM**

The ornamental design for a flagpole light, as shown and described.

DESCRIPTION

FIG. 1 is a top perspective view of the flagpole light showing my new design;

FIG. 2 is a bottom perspective view thereof;

FIG. 3 is a top plan view thereof;

FIG. 4 is a bottom plan view thereof;

FIG. 5 is a left side elevation view thereof;

FIG. 6 is a right side elevation view thereof;

FIG. 7 is a front elevation view thereof;

FIG. 8 is a rear elevation view thereof; and,

FIG. 9 is another perspective view thereof, shown attached to a flagpole.

The broken lines shown on the drawings depict environment only and form no part of the claimed design.
